UNITED STATES PATENT OFFICE.

KAŽIMIRZ CWIKLIŃSKI, OF BLUE ISLAND, ILLINOIS.

SHIP-PROTECTOR.

1,275,402.

Specification of Letters Patent. Patented Aug. 13, 1918.

Application filed December 29, 1917. Serial No. 209,466.

To all whom it may concern:

Be it known that I, KAŽIMIRZ CWIKLIŃSKI, a citizen of Russia, having declared my intention to become a citizen of the United States of America, residing at Blue Island, in the county of Cook and State of Illinois, have invented certain new and useful Improvements in Ship-Protectors, of which the following is a specification.

10 This invention relates to certain new and useful improvements in ship protectors.

The primary object of the invention is the provision of a protector for ships substantially surrounding the hull thereof adapted 15 for cushioning the force of impact exerted by a missile such as a torpedo approaching the ship.

A further object of the device is to provide protecting means for a hull arranged 20 with a plurality of differently tensioned resilient mounting means, the construction being such that an oncoming missile moving beneath the surface of the water will be unable to strike the hull of the ship for injur- 25 ing the same but will be stopped in its progress after the manner of a shock absorber.

A still further object of the invention is the provision of resiliently positioned protectors substantially surrounding the hull 30 of a ship serviceable as buffers in the event of a collision with a boat or dock and being bulletproof for preventing bullets from hitting the hull of the ship.

In the drawings forming a part of this 35 application and in which like designating characters refer to corresponding parts throughout the several views,

Figure 1 is a top plan view of a ship provided with my device.

40 Fig. 2 is a vertical transverse sectional view through a side portion thereof.

Fig. 3 is a horizontal sectional view taken upon line III—III of Fig. 2, and

45 Fig. 4 is a perspective view of one of the brackets employed with the device detached from the hull.

50 My invention is adapted for attachment upon any usual form of ship and is herein illustrated operatively arranged upon the hull 10 of a ship 11, the said ship having a deck 12 and a cabin 13 as well as a forwardly projecting sharpened prow extension 14.

55 Arcuate armor plates 15 formed of bullet- proof metal are arranged resiliently mounted upon the hull 10 substantially surround-

ing the same, the said plates being preferably rectangular in form, normally vertically positioned and reaching from a point substantially upon a level with the keel portion 16 of the hull to a point above the waterline thereof. Mounting brackets 17 are secured in spaced relation upon the hull 10 and the extension 14 thereof, each bracket having two horizontally arranged outwardly 60 projecting sockets 18 and posts 19.

A substantially circular bow spring 20, is slidably arranged upon each pair of posts 19 of each bracket 17 adjustably retained upon the post by means of nuts 21 threaded 70 upon the outer end portions thereof, while shock absorbing springs 22 encircle the posts 19 and are tensioned between the bracket 17 and the free end portions 23 of said bow spring, it being understood that 75 each one of the plates 15 is centrally secured as at 24 to the spring 20.

A socket 25 is centrally arranged within each spring 20, while a helical spring 26 has its pointed ends positioned within the sockets 25 and the upper ones of said sockets 18 of the adjacent bracket 17. An inwardly projecting socket 27 is carried by each plate 15 in horizontal alinement with the lower sockets 18 of the brackets 17 and coiled 85 springs 28 have their opposite ends secured within the sockets 27 and the adjacently arranged lower sockets 18.

The forwardly arranged plates 15 have their forward ends hinged as at 29 to the 90 opposite sides of the extension 14 so that the forwardly positioned armor plates have a swinging movement while the other plates 15 are resiliently supported by the brackets 17 for bodily movement relatively of the hull 95 10 and substantially parallel therewith. It will be understood that when an oncoming missile strikes one of the plates 15, the bow springs 20 will slightly yield as well as the springs 26 and 28, permitting the plate to 100 move inwardly toward the hull, while upon excessive blows struck upon the plates 15, the stronger helical springs 22 will take up the shock through their seating contact with the springs 20 and the inward movement of 105 the plate will be further cushioned and retarded.

Buffer plates may be arranged in this manner substantially surrounding the hull 10, it being noted that the said plates are 110 slightly spaced apart for accommodating the operative movement thereof and a tor-

pedo traveling beneath the surface of the water toward the ship 11 will have its forward progress stopped by striking one of the plates 15 and this will prevent the torpedo 5 from hitting the hull 10. By reason of the general curvature of the plurality of plates 15 when assembled, the device offers little resistance to the travel of the ship through the water although completely serving its 10 purpose of protecting the hull 10 against injury.

What I claim as new is:—

1. In combination with a hull, spaced brackets secured thereto, an outwardly projecting pair of posts carried by each of said brackets, a bow spring for each bracket having its free end portions slidably mounted upon the posts of said bracket, an armor plate vertically secured centrally to a plurality of said bow springs, springs encircling said posts contacting the said brackets and the adjacent sides of said springs, regulating nuts threaded adjacent the free ends of said posts and helical springs between the 25 said brackets and plates.

2. In combination with a hull, spaced brackets secured thereto, an outwardly projecting pair of posts carried by each of said brackets, a bow spring for each bracket having its free end portions slidably mounted upon the posts of said bracket, an armor plate vertically secured centrally to a plurality 20 of said bow springs, springs encircling said posts contacting the said brackets and the adjacent sides of said springs, regulating nuts threaded adjacent the free ends of said posts and helical springs between the said brackets and plates.

3. In combination with a hull, spaced brackets secured thereto, an outwardly projecting pair of posts carried by each of said brackets, a bow spring for each bracket having its free end portions slidably mounted upon the posts of said bracket, an armor plate vertically secured centrally to a plurality 35 of said bow springs, springs encircling said posts contacting the said brackets and the adjacent sides of said springs, regulating nuts threaded adjacent the free ends of said posts, sockets carried by said bow springs and brackets in substantial alinement with each other and helical springs arranged with their opposite ends secured in the said sockets. 40

3. In combination with a hull, spaced brackets secured thereto, an outwardly projecting pair of posts carried by each of said brackets, a bow spring for each bracket having its free end portions slidably mounted upon the posts of said bracket, an armor plate vertically secured centrally to a plurality 45 of said bow springs, springs encircling said posts contacting the said brackets and the adjacent sides of said springs, regulating nuts threaded adjacent the free ends of said posts, sockets carried by said bow springs and brackets in substantial alinement with each other and helical springs arranged with their opposite ends secured in the said sockets. 50

55 In testimony whereof I affix my signature.

KAŽIMIRZ CWIKLIŃSKI.
